UNITED STATES PATENT OFFICE.

SIMON LAKE, OF MILFORD, CONNECTICUT.

STORAGE BUILDING.

Application filed November 11, 1924. Serial No. 749,228.

To all whom it may concern:

Be it known that I, SIMON LAKE, a citizen of the United States, residing at Milford, in the county of New Haven and State of Connecticut, have invented a certain new and useful Improvement in Storage Buildings, of which the following is a full, clear, and exact description.

As is well known, traffic regulations in 10 large cities prohibit the parking of vehicles in the streets, especially in business sections, for more than a specified length of time, and in order to have the automobile retain its features of convenience in transportation, it 15 is essential to provide places where drivers may leave their vehicles for any required period without molestation.

Various expedients have been resorted to for meeting this problem, the most effective 20 being the public garage having numerous floors. But in garages of this type now in use, the manner of handling the vehicles in storing them, and in returning them to their drivers when called for, is so time-consuming 25 as to well nigh defeat their main purpose, that of convenience to the driver.

The object of this invention is to provide a garage of such construction and arrangement, and provided with means for handling vehicles and for transporting them to 30 and from their place of storage of such a nature, that no appreciable amount of time is consumed, and the exasperating delays now common are done away with.

To this end the invention consists in a 35 garage or storage building having a plurality of floors furnishing storage space for a multiplicity of automobiles or other vehicles, or of merchandise, and each of said 40 floors having an open space running from end to end of the building and providing in superposition an elongated elevator well or shaft in which is arranged an elevator carried upon a vertical column, the column 45 being so carried as to be capable of uniform travel in said well from end to end of the building, and the elevator being so mounted upon the column as to be capable of vertical and rotative movement thereon. And the 50 invention consists, further in various instrumentalities, and in the associations of elements to produce the desired utility of the whole, as I will proceed now to explain and finally claim.

In the accompanying drawings illustrating the invention, in the several figures of

which like parts are similarly designated, Figure 1 is a fragmentary sectional perspective view of the interior of one half of a garage or storage building and an elevator and handling mechanism constructed and arranged in accordance with my invention. Fig. 2 is a transverse vertical section of the building and appurtenances. Fig. 3 is a fragmentary plan of the ground floor 60 of the building. Fig. 4 is a fragmentary plan typical of one of the floors of the building above the ground floor, and looking down the elevator shaft or well. Fig. 5 is an enlarged fragmentary longitudinal vertical section of the elevator mechanism. Fig. 6 is an enlarged detail section illustrating a fire curtain and associated mechanism. Fig. 7 is a section taken on the line 7—7 of Fig. 6. 75

In the invention as illustrated, I provide a storage building having a ground floor 1, a basement 2, a runway 3, and a plurality of upper floors 4, surmounted by a pent-house 5 in the roof 6. 80

On the ground floor 1 the building is provided with showrooms and offices 7, and has an entrance passage 8 and an exit passage 9. Checkers' stations 10 and 11 are arranged at the entrance and exit respectively. 85

Columns 12 support the various floors of the building. The ground floor 1 and basement 2 are without partitions or other obstructions aside from the columns 12, but the upper floors are divided by partitions 13 90 furnishing, in effect, separate storage spaces or rooms, which may be completely isolated from each other and from the rest of the building by fireproof curtains (Figs. 6 and 7) comprising sections 14 of metal or other 95 fireproof material hinged or otherwise flexibly connected as at 15 and provided with rods 16 carrying rollers 17 which roll in ways 18 formed in a suitable manner by T irons 19 secured to the columns 12, the 100 rollers serving by their cooperation with the ways 18 to maintain the curtains in fireproof relation to the columns 12 when in lowered position and to guide the curtains in proper alignment when raised, as shown in 105 Fig. 6. The curtains are adapted to fall of their own weight and automatically, upon occurrence of fire, and are controlled by drums 20 around which are wound cables 21 and 22 which travel over pulleys 23 and 24 respectively and support the front and rear ends of the lowermost sections 14 of 110

the curtains. The drums 20 are normally retained in curtain elevating position by trips 25 engaging lugs 26 on the drums and held by any appropriate thermally controlled latches 27. If desired, chemical or the like fire extinguishers 28 may be supported in unstable equilibrium, as shown, upon pivots 29 and are adapted to be tipped over by engagement with them of the lugs 26 upon the automatic release of the curtains.

10 The curtains may be raised and lowered manually, independently of the automatic means, in any suitable manner, by operation 15 of the cables 30.

As shown, the sections 14 of the curtains are provided on their outer edges with eyes 31 through which the cables 21 and 30 pass, and the sections are thus guided and supported.

20 As hereinbefore stated the several upper floors of the building are provided with open spaces *a* forming an elevator shaft or well A, and the ground floor and basement 25 have slots *b* and *c* respectively through which a column extends as next described.

Referring now to the elevator and its associated mechanism, shown in detail in Fig. 5, it will be seen that, in the runway 30 I provide a track 32 upon which travels a carrier or car 33, and in the pent-house 5 I provide a track 34 carrying a travelling carrier or car 35. Supported between and guided by these cars 33 and 35 is a tubular column 36 in which is arranged a vertical shaft 37 provided at its ends with like pinions 38 and 39 meshing with like racks 40 and 41 respectively. This shaft 37 is rotated by a worm and wheel gearing 42 driven by a motor 43. It will thus be seen that upon rotation of the shaft 37 the column 36 and its supporting cars 33 and 35 will be given a travelling movement lengthwise of the building in the elevator 45 shaft or well A and slots *b* and *c*. Due to the combined drive of the top and bottom of the column by means of the rack and gear mechanism 38-40 and 39-41 both ends of the column will travel at the same speed and no swaying or canting of the column will occur.

Embracing the column and slidable vertically thereon is a sleeve 44 provided with a key 45 which engages a keyway 46 formed in the column whereby the sleeve 44 is prevented from turning relatively to the column.

50 Mounted in a circular bearing groove 47 in the sleeve 44 is a bearing ring 48 which supports, by means of suitable sling frames 49, an elevator platform 50 guided on the column 36 by a collar 51 upon which it has a rotative bearing at 52. The platform may be rotated with respect to the column 55 by means of a shaft 53 carrying a pinion

54 meshing with a gear 55 carried by the sleeve 44, and this shaft is driven by a reversible motor 56 through a worm and wheel or other gearing 57.

The elevator platform 50 is raised and lowered on the column 36 by means of a reversible motor 58 carried by the car 33 and driving, through gearing 59, a drum 60 upon which is wound a cable 61 guided by a pulley 62 into the interior of the column 36 and extending to a point adjacent to the top thereof where it passes outside over a pulley 63 and is connected to the sleeve 44 at 64. A counter-weighted cable 65 may be attached to the sleeve 44 at 66 and run over pulley 67 to the interior of the column where its weight 68 is housed.

60 The motors 43, 58 and 56 are controlled, and the operation of the elevator mechanism governed, as desired, through a controller 69, of any approved form, conveniently located in a crow's-nest 70 where the operator stands and which is carried by the sleeve 44. Current for the several motors is taken from rails 71 and 72 preferably mounted in the pent-house 5 and contacted with by brushes or shoes, indicated at 73 from which a multiple cable 74 leads to the controller 69. A slack-adjuster 75 may be carried by the cable 74.

65 The several upper floors of the building may be provided with sectional barriers 76 pivoted at 77 and counter-weighted as at 78, (see Fig. 6) and these barriers will turn down upon the floors when a vehicle is to be run off of the elevator platform, but will prevent a vehicle from rolling off of the floor and into the elevator well.

70 Gates 79 are pivoted at 80 to the elevator platform and may be dropped down, as shown in dotted lines in Fig. 6, when a vehicle is to be unloaded from the platform.

75 As shown in Figs. 1, 3 and 4 an opening *d* may be provided in the ground floor through which the elevator platform may descend to the basement and by which its carrying surface may be aligned with the ground floor.

80 The use, in actual practice, of a storage building constructed in accordance with my invention may be stated as follows:

Assuming that a motorist wishes to leave his automobile in an area in which parking is restricted, and intends to be occupied for a period of time longer than that permitted by the regulations, he drives into the building at the entrance 8 and is handed an identification check by an attendant stationed at 10, a tag bearing an identification character or number corresponding with that borne by the check being attached meanwhile to the automobile in some conspicuous manner. The attendant at the same time makes a note of the probable 85

length of time the automobile will be left in the building. The motorist then parks his automobile in substantially the position indicated at *x*, Figs. 1 and 3, and goes about 5 his business. If he is to be gone only a relatively short time the automobile is left standing where he leaves it, so long as it does not interfere with later arrivals, but, if he is to be gone for a relatively long 10 time, the elevator is brought to the ground floor, is moved longitudinally of the building to a position adjacent to the automobile and is then rotated by means of the motor 56 and gearing 57 and 54-55 to a position 15 in which the automobile may be run straight upon it without backing and filling. The elevator is then raised and moved longitudinally of the building until it reaches the floor and storage space where the automobile is to be deposited, and is brought 20 to a stop, whereupon, the gate 79 being lowered and thereby swinging down the barrier section 76, as shown in dotted lines in Fig. 6, the automobile may be run off of 25 the elevator platform and into the space to which it has been assigned. The automobile may be run off either under its own power or by means of a hook and tackle, as indicated in Fig. 1.

30 When the motorist returns for his automobile, these steps in its handling are reversed and he leaves through the exit 9, depositing his check with the attendant stationed at 11, who at the same time removes 35 the identification tag from the automobile and receives payment of the storage charge.

Obviously, the elevator may be raised or lowered and moved longitudinally of the building in either direction at the same time 40 at the will of the operator stationed in the crow's-nest 70, and it may also, if desired, be rotated while between floors.

It will be apparent that, although the foregoing description is devoted to the handling and storing of automobiles, the invention is not so limited, but may be employed in thus caring for merchandise and the like which must be quickly handled and stored for easy accessibility.

50 By the construction and arrangement of a storage building and an elevator mechanism in accordance with my invention as shown and described, it is possible to park or store a great many automobiles or other 55 vehicles, or a large quantity of merchandise on a limited ground area without sacrificing easy accessibility and rapid handling.

It is to be noted, moreover, that, as indicated at *y*, Fig. 4, the storage rooms or 60 spaces are of sufficient depth to accommodate two automobiles end to end, and that the elevator platform is of a size to accommodate two automobiles side by side. Thus, 65 if the automobile I, Fig. 4, is called for

prior to the automobile II, the one automobile II may be run upon one side of the elevator, the other automobile I run onto the other side of the elevator, and then the first automobile II returned to its storage 70 space.

Various changes in construction are contemplated as within the spirit of the invention and the scope of the following claims.

What I claim is:—

1. In a storage building, a plurality of floors provided with elongated openings together forming an elevator shaft extending longitudinally and vertically the length and height of the building respectively, an elevator arranged in said shaft, means for moving said elevator longitudinally of said shaft, means for raising and lowering the elevator, and means for rotating the elevator, said means being capable of independent actuation. 75

2. In a storage building, a plurality of floors provided with elongated openings together forming an elevator shaft extending longitudinally and vertically the length 80 and height of the building respectively, an elevator arranged in said shaft, means for moving said elevator longitudinally of said shaft, means for raising and lowering the elevator, and means for rotating the elevator, said means being capable of independent actuation separately or simultaneously. 90

3. In a storage building, means defining an elevator shaft extending longitudinally and vertically thereof, a column extending 100 vertically of said shaft and capable of movement longitudinally therein, and an elevator platform carried by and surrounding said column and movable longitudinally thereon. 105

4. In a storage building, means defining an elevator shaft extending longitudinally thereof, a column extending vertically centrally of said shaft, means for supporting said column for movement longitudinally of 110 the shaft, an elevator platform, and means for supporting said platform upon and surrounding said column for travel longitudinally thereof.

5. In a storage building, means defining an elevator shaft extending longitudinally thereof, a column arranged vertically of said shaft, travelling carriers supporting the upper and lower ends of said column, supporting and guiding means for said carriers extending longitudinally of said building and in alignment with said shaft, a vertical drive shaft carried by said column and having driven members at its upper and lower ends, 115 stationary means cooperating with said driven members and with which they react, means for rotating said drive shaft to impart travelling motion to both of said carriers at the same speed and through same to said column, and an elevator platform car- 120

125

130

135

ried by said column and mounted for movement longitudinally thereof.

6. In a storage building, means defining an elevator shaft extending longitudinally thereof, a column arranged vertically of said shaft, travelling carriers supporting the upper and lower ends of said column, tracks providing supporting and guiding means for said carriers, a drive shaft arranged longitudinally of said column, pinions carried at opposite ends of said shaft, stationary racks arranged adjacent to said tracks and meshed by said pinions, means for imparting power to rotate said drive shaft to thereby impart simultaneous travelling movement to said carriers and thence to said column, and an elevator platform carried by said column and mounted for movement longitudinally thereof.
- 15 7. The combination with an elevator shaft of relatively great longitudinal extent as compared with the vertical, of a hollow tubular column arranged vertically thereof, means for supporting and guiding the ends of said column, means for imparting travelling motion to said column longitudinally of the shaft, an elevator platform carried by the column and mounted for movement longitudinally thereof, and a counterweight for said platform arranged for travelling movement longitudinally within said column and connected with said platform.

8. The combination with an elevator shaft of relatively great longitudinal extent as compared with the vertical, of a column arranged vertically thereof, means for supporting and guiding the ends of said column, means for imparting travelling motion to said column longitudinally of said shaft, and an elevator platform carried by the column and capable of longitudinal and rotative movement thereon.

9. The combination with an elevator shaft of relatively great longitudinal extent as compared with the vertical, of a column arranged vertically thereof, means for supporting and guiding the ends of said column, means for imparting travelling motion to said column longitudinally of the shaft, an elevator platform carried by said column, means for imparting movement to said platform longitudinally of said column, and means for rotating said platform upon said column.

10. The combination with an elevator shaft of relatively great longitudinal extent as compared with the vertical, of a tubular column arranged vertically thereof, means for supporting and guiding the ends of said column, means including a drive shaft arranged in the interior of said column for imparting travelling movement thereto longitudinally of the elevator shaft, an elevator platform carried by said column, means for raising and lowering said platform upon

said column, and means for rotating said platform with respect to said column.

11. The combination with an elevator shaft of relatively great longitudinal extent as compared with the vertical, of a column arranged vertically thereof, means for supporting and guiding the ends of said column, means for imparting travelling movement to said column longitudinally of said shaft, a sleeve carried by said column and arranged for longitudinal sliding movement with respect thereto, an elevator platform carried by said sleeve, and means for imparting sliding movement to said sleeve.

12. The combination with an elevator shaft of relatively great longitudinal extent as compared with the vertical, of a column arranged vertically thereof, means for supporting and guiding the ends of said column, means for imparting travelling movement to said column longitudinally of said shaft, a sleeve carried by said column and arranged for longitudinal sliding movement with respect thereto, an elevator platform carried by said sleeve, means for imparting sliding movement to said sleeve, and means for rotating said platform.

13. The combination with an elevator shaft of relatively great longitudinal extent as compared with the vertical, of a column arranged vertically thereof, means for supporting and guiding the ends of said column, means for imparting travelling movement to said column longitudinally of said shaft, a sleeve carried by said column and arranged for longitudinal sliding movement with respect thereto, an elevator platform carried by said sleeve, means for imparting sliding movement to said sleeve, and means carried by said platform and reacting against said sleeve for rotating said platform.

14. The combination with an elevator shaft of relatively great longitudinal extent as compared with the vertical, of a column arranged vertically thereof, means for supporting and guiding the ends of said column, means for imparting travelling movement to said column longitudinally of said shaft, a sleeve carried by said column and arranged for longitudinal sliding movement with respect thereto, cooperating means on said column and sleeve for preventing relative rotation therebetween, an elevator platform carried by said sleeve, means for imparting sliding movement to said sleeve, and means carried by said platform and reacting against said sleeve for rotating said platform.

15. The combination with an elevator shaft of relatively great longitudinal extent as compared with the vertical, of a column arranged vertically thereof, means for supporting and guiding the ends of said column, means for imparting travelling movement to said column longitudinally of said shaft, a

sleeve carried by said column and arranged for longitudinal sliding movement with respect thereto, cooperating means on said column and sleeve for preventing relative rotation therebetween, an elevator platform carried by said sleeve, means for imparting sliding movement to said sleeve, and means

including a drive pinion carried by said platform and reacting against a gear carried by said sleeve for rotating said platform. 10

In testimony whereof I have hereunto set my hand this 10th day of November A. D. 1924.

SIMON LAKE.
